UNITED STATES PATENT OFFICE.

CARL V. MILLER AND BRUCE R. COREY, OF HUNTINGTON, INDIANA.

COMBINED FILTER AND CUT-OFF FOR CISTERNS.

1,181,152.

Specification of Letters Patent.

Patented May 2, 1916.

Application filed June 25, 1915. Serial No. 36,309.

To all whom it may concern:

Be it known that we, CARL V. MILLER and BRUCE R. COREY, citizens of the United States, residing at Huntington, in the county of Huntington and State of Indiana, have invented new and useful Improvements in Combined Filters and Cut-Offs for Cisterns, of which the following is a specification.

This invention relates to a device which may be applied to the supply pipe of a cistern and by the use of which the quality of filtered water entering the cistern may be regulated.

The primary object of the invention is to provide a device of this character which is formed of separable sections, between which is interposed a cut-off member which may be rotated to establish communication between the filter section and openings in a reservoir section, whereby the water passing through the filter section may be diverted into a pipe leading to the cistern or away from the same.

A further object of the invention is to provide a cut-off member for the device which is interposed between a reservoir section, and a filter section, in such a manner as to support the filter section within the reservoir section.

A still further object of the invention is to provide a combined filter and cut-off for the purpose set forth, constructed in such a manner as to enable the several parts comprising the device to be disassembled for cleaning purposes.

With these and other objects in view the invention resides in the improved construction, novel combination and arrangement of parts which will hereinafter be more fully described and particularly pointed out in the claims.

The preferred embodiment of the invention has been illustrated in the accompanying drawing, although no restriction is necessarily made to the precise details of construction therein shown, as changes, alterations and modifications within the scope of the claims may be resorted to when desired.

In the drawing:—Figure 1 is a front elevation of a combined filter and cut-off constructed in accordance with the invention. Fig. 2 is a section on the line 2—2 of Fig. 1, the cut-off being shown in a neutral position. Fig. 3 is a transverse horizontal sectional view on the line 3—3 of Fig. 1, the cut-off

member being shown in a position for establishing communication between the filter section and the compartment connected to the supply pipe of the cistern.

Like characters of reference denote corresponding parts throughout the several views in the drawing.

The improved filter and cut-off comprises a body 1, which is formed from separable sections 2 and 3. The section 3, when united with the section 2 provides a filtering compartment 4, while the section 2 serves as a reservoir for any surplus water which is unable to escape through the supply pipe 5 connected with the cistern. Interposed between the separable sections 2 and 3 is a manually operated cut-off member 5, which establishes communication between the separable sections when united.

The separable section 2 which serves as a reservoir section in the device is substantially semi-circular in cross section for a portion of its length and has the bottom thereof divided into compartments by a transversely extending partition 6. Each of the compartments 7 and 8 has an opening therein and surrounding said openings on the bottom of the sections are depending couplings 9, one of said couplings being connected to the supply pipe of the cistern, while the remaining coupling is connected to the pipe through which the water passing through the device may be diverted from the cistern, neither of the above mentioned pipes being shown in the drawing. The upper front portion of the section 2 is cut away as indicated at 10, to provide a recess 11 in which is disposed the section 3, said section being prevented from lateral movement through an extension 12 extending at right angles to the back of the section 2.

The separable section 3 which may be characterized as the filtering section of the device, is semi-circular in cross section throughout its entire length and has the bottom thereof provided with a centrally disposed aperture 13, which is surrounded by a depending flange 14 on the under side of the section 3. The top of the section 3 is open to provide a passage for water entering the device while the bottom of the section is further provided with a screen fabric 14 upon which may be disposed any filtering medium, such as charcoal or the like.

The partition 6 in the section 2 is provided

in the upper ends thereof with an aperture 15 in which is disposed a trunnion 16 connected with a cut-off member 5 interposed between the bottom of the sections 2 and 3. 5 The upper end of the cut-off member which is tubular in shape is adapted to receive the flange on the bottom of the section 3 and in this manner the cut-off member is mounted for rotation between the sections. In order 10 that the cut-off member may be rotated between the sections, to cause the discharge of water from the filter section into either one or both of the compartments which are connected with the supply pipe of the cistern 15 and the pipe which deflects the water from the cistern, a manually operated rod 17 is provided, one end of which is pivotally connected with the free end of the cut-off member, while the remaining end of the rod extends through an aperture 18 in the front of the section 2.

In order that the weight of the section 3 may be equally distributed upon the cut-off member and allow the same to rotate freely 25 between the sections, the section 2 is provided with a circumferentially extending flange upon the front portion thereof with which the bottom peripheral edge portion of the section 3 is adapted to contact when 30 the sections are united.

The operation of the combined filter and cut-off is as follows: When the sections are united and connected with the pipe leading to the cistern and away from the same, the 35 rod 17 may be actuated to rotate the cut-off member to a position in which water emerging through the cut-off member from the filter section will be directed into either one, or both of the compartments in the 40 section 2. It, of course, being understood that when only a small quantity of water emerges from the filter, the compartment into which it is directed is immediately drained of the same by the opening therein, 45 but should water emerge from the cut-off member with sufficient force to cause the water by contact with the side walls of the section 2 to fill the space or compartment provided by the partition 6 which the water 50 has entered the section 7 will serve as a reservoir for the water until it can find

egress through the pipe with which the compartment is connected.

With reference to the figures in the drawing, it will be seen that a construction for a 55 device of this class has been provided in which the water entering the different compartments thereof may be quickly drained therefrom, thus providing a device of the anti-freezing type, and also each movable 60 section of the combined filter and cut-off may be quickly removed or assembled when desired:

From the foregoing statements taken in connection with the accompanying drawing, 65 it is at once apparent that a combined filter and cut-off for a cistern has been provided which is inexpensive of manufacture, simple in construction and highly efficient in use. 70

Having described the invention, what is claimed is:—

1. A device of the class described, a casing having an open top and a front wall provided with a recess extending from the top 75 of the wall toward the bottom of the casing for the greater portion of the length of the casing, a cut-off member disposed within the casing and below said recess, and a receptacle for filtering material partially supported 80 by the cut-off member and having a front wall closing the recess in the front wall of the casing.

2. In a device of the class described, a casing having a bottom provided with a 85 transversely extending partition having an aperture therein, a cut-off member disposed within the casing and provided with a stud journaled in said aperture, an interior flange upon the front wall of said casing above 90 said partition and lying in a plane parallel with the top of the cut-off member, and a receptacle for filtering material disposed within the casing and bearing upon said flange and the cut-off member. 95

In testimony whereof we affix our signatures in presence of two witnesses.

CARL V. MILLER.
BRUCE R. COREY.
